UNITED STATES PATENT OFFICE

JAMES LOWE, OF AUCKLAND, NEW ZEALAND

VALVE-OPERATING MECHANISM FOR WATER-GAS PLANTS

Application filed April 8, 1927, Serial No. 181,980, and in New Zealand January 20, 1927.

This invention relates to valve operating mechanism and refers more particularly to mechanism for operating and controlling the dampers and valves in a plant for the manufacture of blue water gas, and producer gas such as I have described in my prior United States Patent No. 1,416,042, dated May 16, 1922.

In said patent I have described a plant for the manufacture of blue water gas and producer gas comprising twin generators or producers arranged so that blue water gas is made in one generator while the fire in the other generator is being blown up or revived with air, equal water gas making and producer gas making periods alternating in each generator so that a continuous production of blue water gas and producer gas is kept up. The valves and dampers are interconnected by linkwork and simultaneously operated to effect the change over from making blue water gas to producer gas and vice versa and the simultaneous operation of the valves and dampers may be effected automatically by hydraulic power.

The improved plant has been found to give excellent results and the objects of the present invention are to provide:—

1. An improved mechanism for the automatic operation of the plant by the use of hydraulic power, to effect the change over from the making of blue water gas to producer gas in each generator.

2. An improved mechanism for regulating and controlling the speed of the moving parts of the plant during the period of time when the change over from the making of producer gas to blue water gas is taking place and vice versa, in order to cause a scavenging action whereby the producer gas contained in the generator which was previously being blasted is swept into the producer gas flue instead of being carried forward into the water gas flue as would happen if the change over took place without this scavenging action.

3. An improved mechanism for operating the blast valves so that the open blast valve is rapidly closed at the beginning of the change over and both blast valves remain

shut during the period of scavenging which occurs in the middle of the period when the change over from the making of producer gas to blue water gas is taking place, and towards the end of the change over the other blast valve is rapidly opened.

With these ends in view and such others as may hereinafter appear or are identical thereto, the invention may be said to comprise firstly a valve operating mechanism for the purpose of automatically putting the hydraulic cylinders from which the force to actuate the mechanism controlling the movements of the dampers and valves is derived alternately under pressure and exhaust.

This mechanism may be situated a considerable distance away from the water gas plant and in such a case it is connected by pipes to the hydraulic cylinder arrangement, which actuates the air blast valves and the water gas and producer gas dampers. It is similarly connected by pipes to the hydraulic cylinder arrangement which actuates the steam valve.

The invention also comprises secondly an improved mechanism for regulating and controlling the speed of the hydraulic piston or ram actuating the producer gas and water gas dampers during the period of time when the change over from the making of producer gas to blue water gas is taking place in order to cause the water gas dampers and the producer gas dampers to dwell or move very slowly when near the middle of their stroke with the result that, the blast valves in both generators being closed, and the steam valve on the generator that was previously blasting being open, a scavenging action takes place, whereby the producer gas contained in the generator which was previously blasting is swept into the producer gas flue instead of being carried forward into the water gas flue, as would happen if the change over took place quickly.

The invention also comprises thirdly an improvement in the mechanism or linkwork between the hydraulic cylinder arrangement and the air blast valves, whereby as soon as the hydraulic piston or ram begins to move from either end of its stroke, the blast valve

which is open is rapidly closed and thereafter both blast valves remain closed while the piston or ram moves very slowly towards the middle of its stroke, then towards the end of the stroke the other blast valve is rapidly opened.

It also comprises fourthly an improved combination of working parts consisting of one automatic mechanism, and two sets of hydraulic reciprocating rams or pistons, one of which makes the change over of the steam supply without delay, and the other makes the change over of the producer and water gas dampers and blast valves, but is subject to a delayed action in the middle of its stroke whereby after the blast valve which was open has been closed, and prior to the other blast valve being opened, the producer gas and water gas dampers are caused to dwell in mid position.

The invention is illustrated in the accompanying drawings wherein:

Figure 1 is a front elevation of the improved mechanism for the automatic operation of the plant described in my said patent by the use of hydraulic power,

Figure 2 is an end elevation of the mechanism shown in front elevation by Figure 1,

Figures 3 and 4 show diagrammatically the general arrangement of the automatic mechanism shown in Figures 1 and 2 together with the hydraulic cylinders and linkwork shown in said patent and the connecting pipes between the automatic mechanism and the hydraulic cylinders.

Figure 5 is an enlarged longitudinal section through the valve employed in connection with the invention, and

Figure 6 is a transverse section on the line 40 6-6 of Figure 5.

The automatic mechanism by which the first object is achieved is shown in its preferred construction by Figures 1 and 2 and comprises a lever arm P to which is attached a weight W and adapted to be moved by suitable mechanism and thereafter to move independently of said mechanism under the influence of gravity and thereby quickly effect the operation of the valve or valves Q.

More specifically considered the lever arm P is pivotally mounted at R and when the arm has been moved slightly beyond the neutral or vertical position it falls under the influence of gravity and in falling it engages a lost motion wiper Y connected by means of a link rod S or the like to the controlling valve or valves Q and throws the wiper Y over quickly thereby operating the valve or valves Q.

In one constructional embodiment of the invention the improved valve operating mechanism comprises a spindle or shaft T which is rotated in any suitable manner as by a chain or belt and pulley from a driving

source, said shaft operating a supplementary shaft U through the intermediary of a reducing gear.

A disc V is secured to the supplementary shaft so as to rotate therewith and said disc V is connected by means of a link Z with a sector or quadrant X pivotally mounted on a shaft, the sector X being oscillated or moved backwards and forwards as the disc V is rotated.

Loosely mounted on the same shaft as the sector, is the lever arm P having the weight W at or near the end thereof, said lever arm actuating the controlling valves Q by means of a lost motion connection such as the wiper Y or a pin and slot arrangement between the link and the rod.

Means are provided on the sector X or on the sector shaft for moving the lever arm to the vertical or just beyond the vertical position.

In operation the disc V on the supplementary shaft U during its rotation, oscillates or moves the sector X slowly backwards and forwards. During the backward and forward movement, means on the sector X engage the lever arm P and moves same to just beyond the vertical position, when the weight on the arm becomes operative and throws the arm over quickly to the extreme backward or forward position thereby automatically and practically instantaneously operating the controlling valve or valves Q.

Means may be provided at the extreme positions of the lever arm to act as buffers for said arm.

The improved mechanism operates efficiently and the reducing gear between the driving and supplementary shafts can be arranged so as to drive the disc V on the supplementary shaft U at the desired speed and thereby operate the lever arm P and consequently the controlling valve or valves Q at the periods desired.

In the general arrangement shown diagrammatically on Figures 3 and 4, III is the automatic mechanism which may be placed a considerable distance away from the plant and connected thereto by a hydraulic pipe or pipes IV.

H, H₁ and H₂, H₃ are two hydraulic cylinder arrangements, both of which are connected by hydraulic piping to the valve or valves Q controlled by the automatic mechanism III. One cylinder in each pair is preferably a constant pressure cylinder supplied with water by the pipes V and the other cylinder is subjected to alternate pressure and exhaust by the action of the valve Q. When the valve Q operates, the piston of the H₂, H₃ cylinder arrangement takes a stroke practically instantaneously, thereby reversing the steam supply through the valves C to the generators, but the piston I of the H, H₁ cylinder arrangement is subjected to a delayed

action (which is the second object of this invention) when the piston is about the middle of its stroke thereby causing the water gas dampers G and the producer gas dampers E to dwell in mid position.

5 The piston rod I carries a crosshead J which is connected to the damper rods of two diagonally opposite dampers, that is to say, crosshead J is connected to rod on damper G of one generator and damper E on the other generator.

10 Figure 4 shows the linkwork connections to the valves and dampers on one generator, and the arrangement of the valves and dampers on the other generator is exactly the same except that the valves and dampers are in the opposite position on the other generator.

15 Reference to Figure 4 will show that the (four) rods K attached to the four dampers G, G, E, E, are connected to the (two) swinging levers M pivoted at O and that the (two) coupling rods N for the blast valves B are connected to the (two) swinging levers M₁ pivoted at O₁.

20 The swinging levers M, are actuated in an improved manner (which is the third object of the invention) by coupling rods N so that the open blast valve B is rapidly closed at the beginning of the change over, and both 25 blast valves B remain shut in the middle portion of the stroke, and towards the end of the stroke the other blast valve B is rapidly opened.

30 The connection between the linkwork system on one generator and that on the other is made by means of the crosshead J which is connected to a pair of diagonally opposite damper rods K.

35 The improved mechanism by which the second object is achieved is shown on Figures 40 3 and 4 and comprises a cock II fixed on the pipe to one of the hydraulic cylinders H or H₁ in the cylinder arrangement, should an arrangement of two cylinders be employed, 45 or to one end of a double acting single cylinder should such be used.

40 This cock II is provided with a by-pass so that when it is in the off or closed position a small quantity of water passes through or 50 round it. It is connected to the moving parts by linkwork or gearing VI so that it is fully open when the piston or ram I is at each end of its stroke, and entirely closed except for the by-pass throughout a considerable 55 portion of the stroke of the piston or ram I about mid position. When the automatic mechanism which may be some considerable 60 distance away operates, the cock II being fully open, the piston or ram I moves quickly for the first portion of its stroke. In so doing it closes the cock II and the water being throttled through the by-pass the ram moves very slowly through the middle portion 65 of its stroke until the cock II being

again opened it completes the final portion of its stroke rapidly.

70 By adjusting the area of the by-pass the length of time which the piston or ram I takes to complete its stroke is under control and therefore the length of time during which scavenging takes place is under control. When the ram or piston I is in mid-position both the water gas and producer gas dampers G and E are in mid position and as motion 75 is slow they tend to dwell there.

80 At this portion of the stroke the blast valves B are shut, but one steam valve C being open on the generator which was previously blasting, the contents of that generator are swept into the producer gas flue D instead of being carried forward into the water gas flue F as would happen if the change over took place quickly. Scavenging takes place 85 into the producer gas flue D in preference to the water gas flue F because the resistance in this flue is less than in the other, by reason of the outlet from the water gas flue F being sealed in water. This seal is broken by the 90 pressure of water gas inside the generator when the producer gas damper E is closed and the generator is being steamed.

95 The improved mechanism by which the third object is achieved is shown on Figures 3 and 4 and comprises coupling rods N with lost motion so that the levers M₁ actuating the blast valves B are engaged only during a portion of the stroke of the coupling rods N. The coupling rods N have a stroke equal or proportionate to the stroke of the piston or 100 ram I and they engage pivotally mounted levers M₁ actuating the blast valves B at positions near the pivots O₁ so that the travel of the levers M₁ at the point of engagement is only a small portion of the stroke of the 105 coupling rods N.

110 When the piston or ram I begins to move from either end of its stroke, the blast valve B which is open is rapidly closed by one coupling rod N and thereafter that coupling rod continues its stroke without moving the blast valve lever M₁. The other coupling rod N is moving in the opposite direction but does not engage its blast valve lever M₁ until the stroke is nearly completed. Through the 115 middle portion of their strokes the piston or ram I and the coupling rods N move very slowly, and both blast valves B remain shut until towards the end of the change over, the other blast valve B is rapidly opened as the stroke of the piston or ram I and coupling rods N is completed.

120 This arrangement of linkwork by which the blast valves B are shut for nearly the whole time that the change over is taking place while the reversal of the steam valves C is made practically instantaneously in the beginning of every change over period, enables the plant to be thoroughly scavenged 125 at each change over.

The change overs occur at predetermined equal intervals of time through the agency of the automatic mechanism.

The length of time taken to change over is adjustable by altering the amount of by-pass round the cock II already referred to.

It will be understood that various modifications may be effected in the construction of any of the improved mechanism without departing from the spirit and scope of the present invention.

I claim:

1. A mechanism for periodically controlling the automatic operation of a gas generating plant including, in combination, a control valve, a pivotally mounted lever connected thereto, reduction gearing including pawl and ratchet mechanism for actuating said lever for a portion of its movement, and a weight carried by said lever for actuating the same for the remaining portion of its movement to effect a rapid opening and closing of said valve at periodic intervals.
2. A mechanism in accordance with claim 1, wherein said lever is operated during its first movement by a sector, a disc connected thereto and driven by said gearing, and a constantly rotating shaft operating said gearing.
3. In a mechanism for the control of a gas generating plant, the combination with a hydraulic cylinder including a reciprocating ram, and water gas and producer gas dampers controlled by said ram; of a cock associated with said ram and having a by-pass, and connections between said ram and cock operable when the ram is at either end of its stroke to open said cock and to close the same with the exception of said by-pass after the ram has left either end of its stroke, whereby the water is throttled and the speed of the ram reduced during a considerable part of the intermediate portion of its stroke.
4. In a mechanism for the control of a gas generating plant, the combination with air valves, water gas and producer gas dampers, and gearing for controlling the operation of said dampers; of coupling rods having lost motion actuated by said gearing to operate said air valves only when said rods have nearly completed their strokes.
5. In a mechanism for the control of a gas generating plant, an operating valve, two hydraulic arrangements controlled thereby, steam valves actuated by one of said arrangements, a by-pass cock provided for the other arrangement, water gas and producer gas dampers under the control of said by-pass cock, air valves, and coupling rods with lost motion for actuating said air valves when said rods have nearly completed their strokes.

JAMES LOWE.
